SHIFT MECHANISM

Hugo Benzing, Dresden, Germany, assignor to
 Aktiengesellschaft vorm. Seidel & Naumann,
 Dresden, Germany

Application December 1, 1933, Serial No. 700,530
 In Germany December 10, 1932

5 Claims. (Cl. 197—74)

The invention relates to a shift mechanism for typewriters, calculating machines and the like with simple form of shift, and more particularly machines of that type in which the type bar segment is lifted and lowered in relation to the carriage. It has already been proposed in connection with shift mechanisms to employ alternately extending angle levers, which limit the two extreme positions. These, however, have the disadvantage that the accelerations in respect of the lifting and lowering movements either merely increase or, vice versa, merely decrease. In consequence the one or the other extreme position of the shifted portion terminates or commences merely with hard impact on the joints.

To overcome this drawback the segment or other part shifted is moved through the medium of a U-shaped rocker frame, which is mounted in the frame of the machine and may be lowered or lifted by means of two knee-joints, of which the one engages with the other at the middle joint, is situated approximately at right-angles thereto and is moved by the shift key bars, so that the extreme positions of both knee-joints may be limited by a common stop.

This arrangement has the advantage that with a shift-key movement which is of a uniform nature in itself the shifted part is raised slowly, as far as the middle, to top speed, which following thereon again slowly decreases down to zero in the extreme position.

The arrangement in question does away with all fixed or hard stops for limiting the extreme positions, and provides the possibility of limiting the extended position of the two angle levers by means of merely one stop. This stop, therefore, may be of a soft, sound-damping material, as small irregularities in the transverse direction up to the extended state have no appreciable influence on the position of the shifted part.

It is necessary, however, that the bearings and pivot points be constructed with extreme care. The pivot points, therefore, must be entirely devoid of play, and should be made capable of subsequent readjustment, in order to ensure proper limitation in the extreme positions.

The details of the invention are illustrated in the drawings, in which

Fig. 1 shows a possible form of embodiment of the shift mechanism of a typewriter in the stationary position, viewed from the top, wherein all parts have been omitted which are unnecessary for comprehension of the operation of the shift mechanism.

Fig. 2 is a section according to the line II—II in Fig. 1.

Fig. 3 is a view similar to Fig. 2, with the shift mechanism in the operative position.

Figs. 4—6 show sections through the different pivot points.

Fig. 7 is a section according to the line VII—VII in Fig. 2 through the device for adjusting the stroke.

Fig. 8 shows a part of the locking means for the shift bar in the operative position.

In the frame 1 of the machine there is mounted to rock about a journal 2 a U-shaped frame 3. In the vicinity of the two axes there are provided on this frame lugs 4 bent inwards at right-angles, each of which lugs terminates in a cantilever 5, which may possess a plurality of notches 6, engaged selectively on either side by a spring 7, which is secured in any way to the frame of the machine and serves merely to compensate the mass. The arms of the U-shaped frame 3 are engaged at 8 by links 9, the opposite ends of which are pivoted at 10 to the type bar segment 11. The type bar segment is guided between two vertical guides bars 13 by means of rolls 12. On the side on which the shift mechanism is located the arm of the frame 3 is extended beyond the pivot point 8, and carries at its end a stud 14 engaged by the lower end of a knee-joint, the second joint portion of which is secured in permanent and rotatable fashion in a bearing 16 mounted on the frame of the machine. The middle joint portion 17 of the knee-joint 15a, 15b is engaged by a second knee-joint 18a, 18b with its one end, the opposite end of which is mounted in permanent and rotatable fashion in the bearing 19 on the machine frame. The middle joint portion of this knee-joint is designated 20. The lever 18b of this knee-joint is constructed as an angle lever, the free arm 18c of which possesses at its end a stud 21, which engages in the slot 22 of a lever 24 mounted in permanent and rotatable fashion on the frame of the machine at 23. The lever 24 possesses an arm 24', the end of which thrusts against a pin 25 on the shift key bar 26, which is mounted as usual in permanent and rocking fashion on the frame of the machine at 27, and is connected with the shift key bar on the opposite side of the machine by a shaft.

A spring 28 on the lever 24 has the tendency to hold the knee-joint 18a, 18b in extended or approximately extended position against the stop 31, which is mounted on the frame 1 and is covered with an elastic material, whereby the

type bar segment is safely limited in its upper position. The upper or stationary position of the shift key bar is limited in the known fashion towards the top by a stop bar, which is preferably furnished with an elastic facing and cooperates with abutments 26' on the key bar 26. The springs 29 serve in the known manner to compensate the mass and hold the key bars in the elevated position.

- 10 If it is desired to actuate one of the type situated in the upper row on the type means, the type bar segment, with a carriage which is not movable in the vertical direction, must be moved downwards, either in an inclined or, as in the 15 present case, in a vertical direction. This takes place by depression of one of the shift keys 30. In this manner the lever 26 is rocked downwards about its fulcrum 27. The pin 25 thrusts against the end of the lever 24', and rocks the lever 24 against the action of the spring 28 about its fulcrum 23 into the position according to Fig. 3. This causes the arm 18c of the knee-joint to swing through the medium of the pin 21 about the point 19, whereby the second arm 25 18b, or its joint 20 respectively, which at the same time constitutes the pivot point of the knee-joint 18a, 18b, moves downwards over a corresponding arc and accordingly extends the knee-joint 15a, 15b, until the lever 15b strikes with its abutment 15b', which if desired may also be furnished with a facing of elastic material, against the stop 31, which is mounted on the frame of the machine and is furnished with an elastic facing.
- 30 Since the knee-joint 15a, 15b is secured with one end in the bearing 16, the end point 14 is able to yield only in a downward direction, and describes an arc about the journal 2 on the frame 3. The pin 8 accordingly also moves downwards, and draws the type bar segment in a downward direction through the medium of the link 9. When the lower shift position of the type bar segment has been reached, the knee-joint 15a, 15b is in its extended position and 45 touches the stop 31, in the same fashion as the knee-joint 18a, 18b is extended and thrusts against the stop 31 in the extreme upward shift position of the segment.

The movement of the type bar segment in both 50 directions is dependent on the pivot point 14. Dependent on the fact as to whether the movement of this point is accelerated or retarded, there occurs an acceleration or retardation in the movement of the type bar segment. Upon 55 shifting or when releasing the shift the movements of the point 14, and accordingly of the type bar segment, are as follows: Owing to the angle-lever effect there occurs in the arrangement according to the invention towards the extended position of an evenly moved or also somewhat accelerated point of the knee-joint a considerable delay in the movement of the affected point, i. e., large movements on the part of the joint portion 17 or 20 and correspondingly small movements of the end point 20 or 17, and consequently 14. The lowering and lifting movement of the type bar segment 11 will accordingly also be greatly retarded towards the extreme positions. A gentle shifting motion is obtained, therefore, in both directions.

The position of the stop 31 is so chosen that even should the elastic facing of the stop be somewhat pressed in by use no perceptible variation takes place in the extreme positions of the 75 type bar segment, as the small movements of the

points 17, 20 in the range of the extended position correspond with still smaller movements of the point 14.

An important factor as regards faultless operation of the shift mechanism when employing a system composed of two knee-joints is the proper embodiment of all pivot points and joints.

In Fig. 4 there is shown a possible form of embodiment of a bearing of this kind on enlarged scale such as may conveniently be employed for the fixed bearing points 16 and 19. A block *a*, which is secured in any suitable fashion to the frame of the machine, possesses an incision *b*, so that there is formed a fork-like portion *c*. In the part *c* there is provided a stud *d*, which is conical, tapered, part-spherical or also pointed at its end, and carries, for example, a worm screw, which may be secured in the usual fashion by a nut *e*. The lever *f* to be mounted possesses a boring, which corresponds with the end of the stud and engages with the same, the lever thus being securely mounted.

Figs. 5 and 6 show possible forms of embodiment for pivot points which are not of a permanent kind, such as may be employed for example in connection with the points 8, 10, 14 and 20 (Fig. 5) and the point 17 (Fig. 6). A yoke portion *g* encompasses with its two arms *g*¹, *g*² the levers *h*, *h*¹ or *h*² to be pivotally connected. The studs *d* provided in the two arms *g*¹ and *g*² engage the levers to be mounted on the outer faces in corresponding bores or recesses.

In Fig. 5 the one lever *h*¹ is furnished with a stud *h*¹ passing into a bore in the lever *h*. The lever *h*¹ rests against the lever *h* with a curvature *x* in order to prevent jamming in the joint if, for example, owing to differences in the manufacture, the lever *h* does not swing exactly in the correct plane. According to Fig. 6, three levers are provided, of which the middle lever *h*² possesses on either side studs *h*², which engage in corresponding bores in the adjacent levers. These studs *h*¹ and *h*² in the case of weak levers are preferably formed in a stamping operation by means of correspondingly shaped dies, which act simultaneously on both sides and are hollow at the centre for the purpose of forming the studs. A shoulder 32 on one of the levers supports the yoke *g*, and thus prevents a swinging backwards and forwards and accordingly a disturbing noise.

These bearings offer advantage in various respects, particularly as regards large-scale production and manufacture on a moving belt. The studs may be produced by automatic machines without subsequent finishing, and the levers are stamped with special tools in one operation; the new bearings nevertheless operate accurately, since in a manner of speaking the same are able to yield. Small differences in the manufacture, which are difficult to avoid, may be compensated by adjustment of the bearings. The adjustment may be performed readily as considered necessary, and after any wear which may take place the bearings may be tightened, whereupon the transmission will again occur without play.

For exact adjustment of the distance which the type bar segment is required to move in relation to the carriage upon the shifting operation, an adjustment means is provided which is simple and accurate in operation. The same is to be recognized in Figs. 2 and 3 at the joint 8 and is shown in section on enlarged scale in Fig. 7. In the arms of the U-shaped frame 3 there is furnished an arcuate slot 33, the centre point of

curvature of which coincides with the point 10. In this guide a slide 34, fitting well, may be reciprocated to a certain extent in the direction of the arrow. At the centre of preferably the longer guide edge of the recess 33 forming an arch there is provided a groove 33' disposed vertically to the direction of movement of the slide 34, into which groove there projects the stud 35 of a conical rotary member 36 furnished with a slot suitable for manipulation by means of screw-drivers. This rotary member may be turned in a well fitting bore in the slide 34 and displaces the slide 34 by reason of the fact that the same is anchored at a point 35 of its periphery outside of the slide. The slide at the same time is constructed as a cover plate, and may be firmly connected with the lever arm of the frame 3 by means of screws 37, the bores for which in the cover plate are oblong holes, whereby the rotary member 36, which in the present case is constructed in the form of a truncated cone, is also prevented from falling out. The slide furthermore possesses the bearing 8, which preferably is constructed in accordance with Fig. 5, in which in this case the lever h corresponds with the slide and the lever h' with the intermediate lever 9. If the slide 34 is displaced, the lever arm mounted at the point 2, and accordingly the distance covered upon the shifting of the type bar segment 11 will be varied, without taking effect on the basic position of the type bar segment.

To improve the shift as regards more simple and rapid operation in connection with lengthy shift, there is provided the shift lock described in the following. The key fixing lever 38, which is oscillatory about the same point of rotation 27 as the shift key bar 26 possesses a pin 39, which cooperates in such fashion with a slot guide 40 in a specially formed intermediate lever 42 mounted permanently but in rocking fashion on the machine frame at 41 that upon depression of the locking key 43 this intermediate lever is also rocked downwards in positive fashion, as shown in Fig. 8. The one edge 42' of this intermediate lever is able to slide on a bolt 44 of the shift key bar 26. This working edge possesses at the point corresponding with the depressed position a recess in the form of a quarter of a circle, into which the bolt 44 is able to move. If, now the key system after depression by means of the key 43 is left to itself, there results by reason of the cooperation of a plurality of equally directed turning moments between the bolt 44 and the recess constituting the quarter circle a tension which holds the shift key system in the depressed position until a light pressure against one of the keys 38 produces an oppositely directed turning moment, which overcomes the tension, whereby the intermediate lever 42 moves upwards with the lever 38 by reason of the spring 46 and thus releases the lock. The bolt 44 is mounted in an oblong aperture 45 in the shift key bar 26, so that any differences at this point arising from manufacture may be readily compensated. For reliable operation on the part of the locking means it is essential that the mounting of the intermediate lever takes place between the fulcrum of rotation 27 of the shift key bar 26 and its pressure bolt 44.

It will be understood that no restriction is made to the particular form of embodiment illustrated in the drawings, and that various modifications are quite possible within the meaning of

the above description and the annexed claims without departing from the spirit of the invention.

What I claim as new and desire to secure by Letters Patent is:

1. A shift mechanism for typewriters, calculating machines and the like with simple form of shift, including in combination a U-shaped frame mounted to rock in the frame of the machine to shift the type bar segment, a shift key two knee-joints connecting the shift key and the U-shaped frame for lowering and lifting the said U-shaped frame upon actuation of the shift key, the one of the said knee-joints engaging with the middle joint position of the second knee-joint, being situated approximately at right-angles to the second knee-joint and being moved by the shift key bar, and a common stop for limiting the straight positions of the two knee-joints. 5

2. A shift mechanism for typewriters, calculating machines and the like with simple form of shift, including in combination a U-shaped frame mounted to rock in the frame of the machine to shift the type bar segment, a shift key two knee-joints connecting the shift key and the U-shaped frame for lowering and lifting the said U-shaped frame upon actuation of the shift key, the one of the said knee-joints engaging with the middle joint position of the second knee-joint and being situated approximately at right-angles to the second knee-joint, a two-armed intermediate lever mounted on the machine frame for operating the said first knee-joint upon actuation of the shift key, a spring acting on the said lever and tending to hold the said first knee-joint in the extended position, and a common stop for limiting the straight positions of the two knee-joints. 10 15

3. A shift mechanism for typewriters, calculating machines and the like with simple form of shift, including in combination a U-shaped frame mounted to rock in the frame of the machine to shift the type bar segment, a shift key, two cooperating knee-joints connecting the shift key and the U-shaped frame for lowering and lifting the said U-shaped frame upon actuation of the shift key, a common stop for limiting the straight positions of the two knee-joints, and an adjustment means mounted in the said U-shaped frame for exact adjustment of the extent of movement of the type bar segment, the said adjustment means including adjustable bearing joints mounted in arcuate guide slots in the arms of the said U-shaped frame, links connecting the arms of the U-shaped frame with the type bar segment, supporting bearings for the said links carried by the said bearing joints, and a cranked pin for displacing the said joints. 20 25 30 35

4. A shift mechanism for typewriters, calculating machines and the like with simple form of shift, including in combination a U-shaped frame mounted to rock in the frame of the machine to shift the type bar segment, a shift key, two cooperating knee-joints connecting the shift key and the U-shaped frame for lowering and lifting the said U-shaped frame upon actuation of the shift key, a common stop for limiting the straight positions of the two knee-joints, and an adjustment means mounted in the said U-shaped frame for exact adjustment of the extent of movement of the type bar segment, the said adjustment means including adjustable bearing joints mounted in arcuate guide slots in the arms of the said U-shaped frame, links connecting the arms of the U-shaped frame with the type bar segment, supporting bearings for the said links carried by 40 45 50 55 60 65 70 75

the said bearing joints, a slide reciprocating in the arm of the said U-shaped frame, a rotary member having its longitudinal axis vertical to the direction of movement of the said slide, a 5 cranked pin for displacing the said joints mounted on the said rotary member, the said rotary member co-operating with its jacket surface only in part with a bore in the wall of the said slide, and a projection on the periphery of the end face 10 of the said rotary member, the rotary member upon its rotation swinging longitudinally about the said projection.

5. A shift mechanism for typewriters, calculating machines and the like with simple form

of shift, including in combination a U-shaped frame mounted to rock in the frame of the machine to shift the type bar segment, a shift key 5 two co-operating knee-joints connecting the shift key and the U-shaped frame for lowering and lifting the said U-shaped frame upon actuation of the shift key, links connecting the arms of the U-shaped frame with the type bar segment, adjustable joints devoid of play for connecting all levers, knee-joints and links of the shift mechanism, and a common stop for limiting the straight 10 positions of the two knee-joints.

HUGO BENZING.
